[57] CLAIM

The ornamental design for a magnetic curtain hook, as shown and described.

DESCRIPTION

FIG. 1 is a perspective view of a magnetic curtain hook, showing my new design;

FIG. 2 is a top plan view;

FIG. 3 is a left side elevation with the right side elevation being the mirror image thereof;

FIG. 4 is a front elevation;

FIG. 5 is a rear elevation; and,

FIG. 6 is a bottom plan view.

The cross-hatching shading shown on FIG. 5 represents a magnetic surface.
